UNITED STATES PATENT OFFICE.

HOWARD M. BARBER, OF STONINGTON, CONNECTICUT, ASSIGNOR TO C. B. COTTRELL & SONS COMPANY, OF STONINGTON, CONNECTICUT, A CORPORATION OF DELAWARE.

ROTARY WEB-PRINTING PRESS.

Application filed January 17, 1924. Serial No. 686,794.

To all whom it may concern:

Be it known that I, HOWARD M. BARBER, a citizen of the United States, and resident of Stonington, in the county of New London and State of Connecticut, have invented a new and useful Improvement in Rotary Web-Printing Presses, of which the following is a specification.

My invention relates to novel means in a rotary web printing press for taking up, within certain limits, a varying amount of material in a web between the portions which are to be printed, so as to space such printed matter varying distances apart according to the length of sheets to be cut from the web, the printed matter on every sheet being located in the same position.

My invention more particularly includes two rotary carriers, the one serving as the impression cylinder bearing an annular series of floating web clamping jaws, and the other carrier bearing an annular series of floating tucking blades arranged to tuck the web into their respective clamping jaws, the jaws and blades, either one or both, being radially adjustable to take up varying amounts of the web material between the portions to be printed, the jaws being locked against movement relative to their cylinder, to hold the impression portions of the web snugly against the impression surfaces of the cylinder during the printing operation.

A practical embodiment of my invention is represented in the accompanying drawings, in which—

Fig. 1 represents diagrammatically in side elevation a multi-color rotary web printing press with my improvements applied thereto, the web being shown threaded through the press.

Fig. 2 represents a detail vertical cross section through the press on an enlarged scale, with the clamping jaw locking mechanism (illustrated in Figs. 12, 13 and 14) removed.

Fig. 3 represents a detail section taken in the plane of the line III—III of Fig. 2.

Fig. 4 represents a fragmentary section taken in the plane of the line IV—IV of Fig. 2.

Fig. 5 represents a fragmentary section taken in the plane of the line V—V of Fig. 2.

Fig. 6 represents a view of one of the end

supporting brackets for the radially adjustable web tucking blades.

Fig. 7 represents a view of one of the end supporting brackets for the radially adjustable web clamping jaws.

Fig. 8 represents a face view of one of the tucking blades.

Fig. 9 represents an end view of the same.

Fig. 10 represents an end view of one of the impression segments.

Fig. 11 represents a side view of the same.

Fig. 12 represents a detail section of the clamping jaw locking mechanism.

Fig. 13 represents a detail section taken in the plane of the line XIII—XIII of Fig. 12.

Fig. 14 represents a detail section on an enlarged scale, taken in the plane of the line XIV—XIV of Fig. 12.

Fig. 15 represents a detail plan view, partly in section, of one of the sets of clamping jaws.

Fig. 16 represents a detail side view of the same, partly in section.

Fig. 17 represents one end view of the same.

Fig. 18 represents the other end view.

Fig. 19 represents a detail section taken in the plane of the line XIX—XIX of Fig. 16.

The frame of the multi-color rotary web printing press is denoted by 1. The web 3 is led from the supply roll 2 to the rewinding roll 4, successively around the rolls 5 and 6, the feed drum 7, the slack take-up roller 8, the impression cylinder 9, the roll 10, the slack take-up roller 11 and the rolls 12, 13, and 14 of the rewinding mechanism.

The rolls of the rewinding mechanism are driven at a surface speed slightly in excess of that of the rolls of the web feeding mechanism so that the web is always wound under proper tension to give a perfectly rewound roll.

The drive for the two mechanisms, in the present instance, includes the shafts 15 and 16, the shaft 15 having at one end the bevel gear connection 17, 18, with the web feed drum 7, and at the other end the bevel gear connection 19, 20, 21 with the corresponding end of the shaft 16.

The other end of this shaft 16 has the bevel gear connection 22, 23, with the rewinding roll 14. Suitable web feed rolls 24, 25 are provided for coaction with the web feed drum 7 to ensure the accurate feeding of the web to the impression cylinder 9.

This impression cylinder 9 is provided with an annular series of lengthwise recesses 26, equally spaced apart around the peripheral surface of the cylinder, forming 5 a plurality of impression segments 27, arranged to coact with one or more form cylinders 28 to print the desired matter on the web during its passage through the press. In the present instance I have shown four 10 of these form cylinders 28, their inking devices being indicated diagrammatically by 29 so that a multi-color impression may be made at spaced intervals along the web.

An annular series of floating tucking 15 blades 30 are carried by the rotary cylinder 31, which blades are arranged to be brought into and out of coaction with their respective sets of web clamping jaws 32, 32 carried by the impression cylinder 9. These 20 tucking blades 30 are arranged equal distances apart around the periphery of the rotary cylinder 31 and are constructed, mounted and operated as follows:

Two end hangers 33, 33 for each blade are 25 provided with trunnions 34, 34, pivotally mounted in brackets 35, 35, secured to the opposite ends of the cylinder 31, which hangers are connected by a bar 36 to which the tucking blade 30 is adjustably secured 30 by providing the blade with a plurality of transversely elongated slots 37, through which set screws 38 pass into the bar 36. The tucking blades are thus mounted to swing on the trunnions 34, 34 and are radially adjustable on the bar 36 with respect to 35 their cylinder 31.

At one end of the cylinder 31 the trunnion 34 is provided with an arm 39 bearing 40 a stud or roller 40, arranged to travel in the groove of a cam 41 rotatively adjustable on the main frame by providing the cam with ears 42, having circumferentially elongated grooves 43, through which pass the set screws 44. The annular series of web 45 clamping jaws 32, 32 are located in the recesses 26 of the impression cylinder 9, each clamping jaw mechanism being constructed, arranged and operated as follows:

The end hangers 45, 45 are provided with 50 trunnions 46, 46 pivoted in radially adjustable brackets 47, 47 secured to the opposite ends of the impression cylinder 9 by providing each bracket with elongated slots 48, through which set screws 49 pass into the cylinder. These end hangers 45, 45 are connected by the jaw carrying bars 50, 50, which which bars are mounted to rock in the end hangers for opening and closing 55 their jaws 32, 32.

60 The clamping jaws are rocked bodily to float them for properly receiving their tucking blade, at the web tucking operation by providing one end trunnion 46 with an arm 51 bearing a stud or roller 52 arranged to pass through the groove of a radially ad-

justable fixed box cam 53, which cam is secured to the main frame 1 by providing the cam with ears 54, having radially elongated slots 55, through which set screws 56 pass into the frame.

70 The web clamping jaws 32, 32 are opened for the web tucking operation by providing the jaw bars 50, 50 with arms 57, 57 between the free ends of which I locate a double cam 58 at the inner end of a rock shaft 59 passing axially through the trunnion 46, the outer end of which rock shaft is provided with an arm 60 bearing a stud or roller 61, arranged to ride over a radially adjustable fixed cam 62, secured to the main frame, 75 said cam being provided with ears 63 having radially elongated slots 64, through which set screws 65 pass into the main frame.

80 For holding the web clamping jaws normally closed I provide the jaw bars 50, 50 with arms 66, 66, between which a coil spring 67 is located.

85 The web clamping jaws are opened to release the web after the printing operation 90 thereon, by providing a radially adjustable fixed cam 68, over which the stud or roller 61 rides, which cam is provided with ears 69 having radially elongated slots 70 through which pass the set screws 71, into 95 the main frame.

To lock the web clamping jaws rigidly 100 in position, except during their web receiving and grasping operation, I provide the outer face of one of the end hangers 45 with a groove 72 arranged to receive a locking tongue 73 carried by the inner end of 105 longitudinally sliding bars 74, 74, which pass through the end of the cylinder and are connected at their outer ends to a two armed rocking lever 75, 76, pivoted at 77 to a stud 78 carried by the cylinder. A coil spring 79 is located between the lever arm 76 and the cylinder, tending to hold the locking tongue 73 in engagement with the 110 groove 72. The clamping jaws are thus locked against relative movement with respect to the cylinder during the printing operation, thereby holding the web snugly 115 in position against the impression segments. 115

To release the clamping jaws to permit them to be floated into proper coaction with their tucking blade to clamp the web, I provide the lever arm 76 with a stud or roller 80, arranged to ride along the radially adjustable fixed cam 81 secured to the main frame, said cam being provided with ears 82 having radially elongated slots 83 through which the set screws 84 pass into 120 the main frame.

125 It will thus be seen that the clamping jaws of each set are not only mounted to swing on their trunnions for floating them into proper coaction with their tucking blade, but that they are also radially ad-

justable to bring them into proper position with respect to the said tucking blade, the jaws being also opened and closed at the proper intervals for receiving and releasing the web and also being held against relative movement at the proper time irrespective of their radial adjustment.

The impression segments 27 of the impression cylinder 9 are removably secured 10 to the cylinder by screws 85, said segments being faced with suitable pliable material 86 to ensure a good printing impression. The removability of the segments permits their replacement from time to time, as required, due to wear, defects or injury, without requiring the replacement of the entire cylinder surfaces.

In operation:

Each set of web clamping jaws 32, 32, 20 and its coacting tucking blade 30 are adjustable radially, either one or both, to provide for taking up more or less material between the impression portions of the web, it being understood that the controlling 25 cams for the jaws and blades are also adjusted to keep the parts in their proper operative relationships.

The web, as it enters the press, is fed at a predetermined speed by the feeding drum 30 7 and its coacting feed rolls 24, 25. The web passes around the take-up roll 8 and from thence to the impression cylinder 9 where the desired amount of material is forced inwardly by each tucking blade into 35 its set of web clamping jaws, the blade and jaws being floated into position for proper coaction. As each blade is withdrawn from its jaws, the jaws are brought together to grasp the material between them. The jaws 40 are then locked against relative movement with respect to the cylinder as the web is carried by the cylinder under the printing forms to receive the impressions upon the portions of the web which are held snugly 45 down on the impression surfaces of the cylinder, to ensure the best possible printing. After the printing operation is completed, the clamping jaws are released and the web 50 is rewound on the roll 4, the web passing around the take-up roll 11 in its progress from the impression cylinder to the said rewinding roll. The web rewinding mechanism may be driven at a surface speed 55 slightly in excess of that of the web feeding mechanism so as to impart proper tension to the web as it is being rewound.

From the above description it will be seen that I have provided a simple and effective means for varying the spaces between successive complete printed impressions on the web, to suit different lengths of sheets to be cut therefrom, thereby ensuring the proper positioning of the printed matter on all of the sheets.

It is evident that various changes may

be resorted to in the construction, form and arrangement of the several parts without departing from the spirit and scope of my invention; hence, I do not wish to be limited to the particular embodiment herein shown 70 and described, but—

What I claim is:—

1. In a rotary web printing press, an impression cylinder having an annular series 75 of spaced impression surfaces, means for forcing a predetermined amount of the web material into the cylinder between said impression surfaces, and means carried by the cylinder for holding the web snugly against the impression surfaces during the printing 80 operation.

2. In a rotary web printing press, an impression cylinder having an annular series 85 of spaced impression surfaces, means for forcing a predetermined amount of the web material into the cylinder between said impression surfaces, and means carried by the cylinder for holding the web snugly against the impression surfaces during the printing 90 operation comprising, an annular series of clamping devices arranged to grasp and hold the forced-in web material.

3. In a rotary web printing press, an impression cylinder having an annular series 95 of spaced impression surfaces, means for forcing a predetermined amount of the web material into the cylinder between said impression surfaces, and means carried by the cylinder for clamping said forced-in web 100 material and holding it during the printing operation.

4. In a rotary web printing press, an impression cylinder having an annular series 105 of spaced impression surfaces, means for forcing a predetermined amount of the web material into the cylinder between said impression surfaces, means carried by the cylinder for clamping said forced-in web material and holding it during the printing operation, and means for adjusting the relationship between the web forcing-in and clamping means, whereby more or less web material may be forced in and clamped between said impression surfaces. 115

5. In a rotary web printing press, an impression cylinder having an annular series 120 of spaced impression surfaces, tucking blades for forcing a predetermined amount of the web material into the cylinder between said impression surfaces, and clamping jaws carried by the cylinder for clamping said forced-in web material and holding it during the printing operation.

6. In a rotary web printing press, an impression cylinder having an annular series 125 of spaced impression surfaces, tucking blades for forcing a predetermined amount of the web material into the cylinder between said impression surfaces, clamping

- jaws carried by the cylinder for clamping said forced-in web material and holding it during the printing operation, and means for adjusting the relationship between the 5 tucking blades and clamping jaws, whereby more or less of the web material may be forced in and clamped between said impression surfaces.
7. In a rotary web printing press, an impression cylinder having an annular series 10 of removable spaced impression segments, an annular series of web clamping devices carried by said cylinder between said segments, and means for forcing the web material into said clamping devices.
8. In a rotary web printing press, an annular series of removable spaced impression segments, pliable impression members 20 carried thereby, an annular series of web clamping devices carried by said cylinder between said segments, and means for forcing the web material into said clamping devices.
9. In a rotary web printing press, means 25 for taking up a predetermined amount of material in the web at spaced intervals comprising, two rotary cylinders, an annular series of web clamping devices carried by one cylinder, and an annular series of coacting web tucking devices carried by the other cylinder.
10. In a rotary web printing press, means 35 for taking up a predetermined amount of material in the web at spaced intervals comprising, two rotary cylinders, an annular series of web clamping devices carried by one cylinder, an annular series of coacting web tucking devices carried by the other cylinder, and means for adjusting the clamping devices radially with respect to 40 their cylinder to take up more or less of the web material.
11. In a rotary web printing press, means 45 for taking up a predetermined amount of material in the web at spaced intervals comprising, two rotary cylinders, an annular series of web clamping devices carried by one cylinder, an annular series of coacting web tucking devices carried by the other cylinder, and means for adjusting the tucking devices radially with respect to their cylinder to take up more or less of the web material.
- 55 12. In a rotary web printing press, means for taking up a predetermined amount of material in the web at spaced intervals comprising, two rotary cylinders, annular series of coacting web tucking and clamping devices carried by their respective cylinders, and means for adjusting the clamping devices and the tucking devices radially with respect to their cylinders to take up more or less of the web material.
- 60 13. In a rotary web printing press, means for taking up a predetermined amount of material in the web at spaced intervals comprising, two rotary cylinders, annular series of coacting web tucking blades and clamping jaws carried by their respective 70 cylinders.
14. In a rotary web printing press, means for taking up a predetermined amount of material in the web at spaced intervals comprising, two rotary cylinders, annular series 75 of coacting web tucking blades and clamping jaws carried by their respective cylinders, and means for adjusting the jaws radially with respect to their cylinder to take up more or less of the web material. 80
15. In a rotary web printing press, means for taking up a predetermined amount of material in the web at spaced intervals comprising, two rotary cylinders, annular series 85 of coacting web tucking blades and clamping jaws carried by their respective cylinders, and means for adjusting the blades radially with respect to their cylinder to take up more or less of the web material.
16. In a rotary web printing press, means 90 for taking up a predetermined amount of material in the web at spaced intervals comprising, two rotary cylinders, annular series of coacting web tucking blades and clamping jaws carried by their respective cylinders, and means for adjusting the jaws and the blades radially with respect to their cylinders to take up more or less of the web material. 95
17. In a rotary web printing press, means 100 for taking up a predetermined amount of material in the web at spaced intervals comprising, two rotary cylinders and annular series of coacting floating tucking blades and floating clamping jaws carried by their respective cylinders. 105
18. In a rotary web printing press, means 110 for taking up a predetermined amount of material in the web at spaced intervals comprising, two rotary cylinders, annular series of coacting floating tucking blades and floating clamping jaws carried by their respective cylinders, and means for adjusting the jaws radially with respect to their cylinder to take up more or less of the web material. 115
19. In a rotary web printing press, means 120 for taking up a predetermined amount of material in the web at spaced intervals comprising, two rotary cylinders, annular series of coacting floating tucking blades and floating clamping jaws carried by their respective cylinders, and means for adjusting the blades radially with respect to their cylinders to take up more or less of the web material. 125
20. In a rotary web printing press, means 130 for taking up a predetermined amount of material in the web at spaced intervals comprising, two rotary cylinders, annular series of coacting floating tucking blades and float-

- ing clamping jaws carried by their respective cylinders, and means for adjusting the jaws and blades radially with respect to their cylinders to take up more or less of 5 the web material.
21. In a rotary web printing press, means for taking up a predetermined amount of material in the web at spaced intervals between the impression portions of the web 10 comprising, an impression cylinder having an annular series of spaced impression surfaces, an annular series of spaced impression surfaces, an annular series of web clamping jaws located between said impression surfaces, and a rotary tucking blade carrying cylinder having an annular series 15 of tucking blades arranged to coact with said web clamping jaws.
22. In a rotary web printing press, means for taking up a predetermined amount of material in the web at spaced intervals between the impression portions of the web comprising, an impression cylinder having an annular series of spaced impression surfaces, an annular series of web clamping jaws located between said impression surfaces, a rotary tucking blade carrying cylinder having an annular series of tucking blades arranged to coact with said web 20 clamping jaws, and means for adjusting the jaws radially with respect to their cylinder to take up more or less of the web material.
23. In a rotary web printing press, means for taking up a predetermined amount of material in the web at spaced intervals between the impression portions of the web comprising, an impression cylinder having an annular series of spaced impression surfaces, an annular series of web clamping 25 jaws located between said impression surfaces, a rotary tucking blade carrying cylinder having an annular series of tucking blades arranged to coact with said web clamping jaws, and means for adjusting the jaws radially with respect to their cylinder to take up more or less of the web material.
24. In a rotary web printing press, means for taking up a predetermined amount of material in the web at spaced intervals between the impression portions of the web 30 comprising, an impression cylinder having an annular series of spaced impression surfaces, an annular series of web clamping jaws located between said impression surfaces, a rotary tucking blade carrying cylinder having an annular series of tucking blades arranged to coact with said web clamping jaws, and means for adjusting the 35 jaws radially with respect to their cylinder to take up more or less of the web material.
25. In a rotary web printing press, an impression cylinder having an annular series of spaced impression surfaces and recesses,
- web clamping means located in said recesses, 65 and web tucking means for forcing a predetermined amount of the web material into said recesses, into engagement with said web clamping means.
26. In a rotary web printing press, an impression cylinder having an annular series of spaced impression surfaces and recesses, an annular series of web clamping jaws located in said recesses, and web tucking means for forcing a predetermined amount 70 of the web material into said recesses, into engagement with said web clamping jaws.
27. In a rotary web printing press, an impression cylinder having an annular series of spaced impression surfaces and recesses, an annular series of web clamping jaws located in said recesses, and an endless series 75 of web tucking blades for forcing a predetermined amount of the web material into said recesses, into engagement with said web clamping jaws.
28. In a rotary web printing press, means for taking up a predetermined amount of material in a traveling web at spaced intervals along the same comprising, an impression cylinder, means for passing the web around the same, radially adjustable web clamping jaws on the impression cylinder, a coacting cylinder, and radially adjustable web tucking blades carried thereby and coacting with the clamping jaws to tuck the web 80 thereinto.
29. In a rotary web printing press, means for taking up a predetermined amount of material in a traveling web at spaced intervals along the same comprising, an impression cylinder, means for passing the web around the same, radially adjustable web clamping jaws on the impression cylinder, a coacting cylinder, radially adjustable web tucking blades carried thereby and coacting with the clamping jaws to tuck the web 85 thereinto, and means for locking the clamping jaws against relative movement during the printing operation.
30. In a rotary web printing press, means for taking up a predetermined amount of material in a traveling web at spaced intervals along the same comprising, an impression cylinder, means for passing the web around the same, radially adjustable web clamping jaws on the impression cylinder, a coacting cylinder, radially adjustable web tucking blades carried thereby and coacting 90 with the clamping jaws to tuck the web thereinto, and means for locking the clamping jaws against relative movement during the printing operation comprising, a cam 95 controlled locking device.
- In testimony, that I claim the foregoing 100 as my invention, I have signed my name as this fourteenth day of January A. D. 1924.
- HOWARD M. BARBER.
